Primary Examiner — Ian Simmons*Assistant Examiner* — Rhea Shields*(74) Attorney, Agent, or Firm* — Botkin & Hall, LLP(57) **CLAIM**

The ornamental design for a baked goods box, as shown and described.

DESCRIPTION

FIG. 1 is a perspective view of the baked goods box;

FIG. 2 is a top view of the box of FIG. 1;

FIG. 3 is a front view of the box of FIG. 1;

FIG. 4 is a back view of the box of FIG. 1;

FIG. 5 is a bottom view of the box of FIG. 1; and,

FIG. 6 is a left side view of the frame of FIG. 1, the right side view being mirror symmetrical.

In FIG. 6 the broken line indicates a perforation and forms a part of the claim.
